Patented Aug. 29, 1922.

FIG. 1.

FIG. 5.

FIG. 6.

WITNESS:

INVENTOR.
FRANK M. STOLL

BY
G. J. Collamer
ATTORNEY.

UNITED STATES PATENT OFFICE.

FRANK M. STOLL, OF DENVER, COLORADO.

LUGGAGE RACK.

1,427,173.

Specification of Letters Patent. Patented Aug. 29, 1922.

Application filed December 15, 1920. Serial No. 430,916.

To all whom it may concern:

Be it known that I, FRANK M. STOLL, a citizen of the United States, residing at Denver, in the county of Denver and State 5 of Colorado, have invented certain new and useful Improvements in Luggage Racks, of which the following is a specification.

This invention relates to luggage racks for automobiles and its main object is to 10 provide a collapsible device of simple, light and strong construction which in conjunction with the running board of a motor vehicle, forms a safe and capacious receptacle for suit cases and other articles of luggage 15 and merchandise.

Another object of my invention is to provide a luggage rack of this character which in its collapsed condition occupies an unobtrusive position on the running board to 20 which it is applied.

With the above and other objects in view all of which will fully appear in the course 25 of the following description, my invention consists in the construction and arrangement of parts shown in the accompanying drawings in the various views of which like parts are similarly designated, and in which—

Figure 1 is a side elevation of my im- 30 proved luggage rack in its operative position on the running board of a motor vehicle;

Figure 2, a section on the line 2—2, Figure 1;

Figure 3, an enlarged section taken on the same line showing the rack in its collapsed condition;

Figure 4, a fragmentary plan view of one of the ends of the rack, looking in the 40 direction of the arrow B, Figure 2;

Figure 5, an enlarged view of the hinge connection between the longitudinal rails of the rack and the end pieces of the same;

Figure 6, an enlarged face view of one 45 of the brackets by which a rack is fastened to the running board, and

Figure 7, an edge view of the same, looking in the direction of the arrow A, Figure 6.

50 Referring more specifically to the drawings the reference character 2 designates the running board of a motor vehicle to which the luggage rack is applied.

The rack consists of a number of parallel 55 rails 3 of channel or angle section which in practise extend longitudinally with relation

to the running board and which are mounted in spaced relation to each other upon two uprights 4 of lazy tongs construction.

Pivotaly connected at the ends of the 60 upper and lower rails are two lazy tongs wings 5 which in the operative position of the rack close the spaces over the running board of the vehicle at the ends thereof.

The pivotal connection between the rails 65 and the wings or end members of the structure is established through the medium of lugs 6 best shown in Figure 5 of the drawings.

The members 5 extend normally at right 70 angles to the rails, as shown in Figure 2, and they are readily moved about their pivots in parallel relation to the same as indicated in broken lines in Figure 1, preparatory to folding the parts of the device to 75 together.

The rack is mounted on the running board through the medium of two angle brackets 7 which are fastened in a depending position with relation to the forward edge 80 thereof by means of clamping screws 8.

Each bracket has horizontal and arcuate slots 9 and 10 to receive pivot pins 11 and 12 on the lazy tongs uprights of the structure through the medium of which the rack is 85 fastened to the brackets.

One of the diagonal levers of the lazy 90 tongs at the lower extremity thereof is to this end extended as at 13 and the pivot pins passing through the slots of the respective brackets are connected to said extended levers.

The pins passing through the horizontal 95 slots of the brackets are connected at the ends of the extensions 13, while those passing through the arcuate slots of the same at the points at which the extended levers are connected with the adjoining members of the lazy tongs and one or both of the last-mentioned pivot pins of the two uprights 100 may be threaded for the application of wing-nuts 14 by which the structure is clamped in its adjusted positions.

In the drawings but one nut has been 105 shown as applied to the pivot pin of the forward upright of the luggage rack, it being understood that the clamping action of this single nut is sufficient to maintain the entire structure in its extended position.

In the operative position of the luggage 110 rack as shown in Figures 1 and 2 of the drawings, the rail 3 extends longitudinally

in spaced relation to each other above the other edge of the running board and the end members 5 are positioned at right angles to the rails to close the spaces between 5 their ends and the body of the vehicle.

The rack is collapsed by folding the end-members upon the rails as indicated in broken lines in Figure 1 and loosening the clamp nut 14 which maintains the structure 10 in its extended condition.

Owing to the lazy tongs construction of the uprights and the wings the entire device is readily folded by downward movement of the rails, and it will be observed that in its 15 collapsed condition the entire device occupies but a space forward of and below the longitudinal edge of the running board substantially equal to the combined width of its rails.

Having thus described my improved luggage rack in the most convenient and practical forms at present known to me, I desire it understood that variations in the construction and arrangement of its parts may be 25 resorted to within the spirit of my invention as defined in the hereunto appended claims.

What I claim and desire to secure by Letters-Patent is:

1. A luggage rack for automobiles comprising in combination with the running board of an automobile, brackets attached at the edge thereof, and each having horizontal and arcuate slots, lazy tongs uprights having pivot pins in the slots of the brackets, 30 rails connected to the uprights, and means for maintaining the uprights in an extended 35 position.

2. A luggage rack for automobiles comprising in combination with the running 40 board of an automobile, brackets attached at the edge thereof, and each having horizontal and arcuate slots, lazy tongs uprights

having pivot pins in the slots of the brackets, rails connected to the uprights, and a nut applied to one of said pins for clamping the 45 uprights in an extended position.

3. A collapsible luggage rack comprising in combination with the running board of an automobile, brackets extending below the edge thereof, lazy tong uprights movably 50 connected to the brackets, parallel rails pivotally connected to the uprights and spaced to fall upon each other when said uprights are in a folded condition, and means on the brackets engaging with the uprights for 55 locking the latter in their extended position.

4. A collapsible luggage rack for automobiles comprising in combination brackets adapted for connection at the edge of the running board of an automobile, lazy tong 60 uprights movably connected outside of the brackets, parallel rails pivotally connected to the uprights and spaced to fall upon each other when said uprights are in a folded condition, end members at the end of the 65 rails to fold upon the same, and means on the brackets engaging with the uprights for locking the latter in their extended position.

5. A collapsible luggage rack for automobiles comprising in combination brackets 70 adapted for connection at the edge of the running board of an automobile, lazy tong uprights movably connected outside of the brackets, parallel rails pivotally connected to the uprights and spaced to fall upon each 75 other when said uprights are in a folded condition, lazy tong end members at the ends of the rails, adapted to fold in conformity with the uprights, and means for locking the uprights in their extended position.

In testimony whereof I have affixed my signature.

FRANK M. STOLL.
